Fig. 5

To all whom it may concern:

Be it known that I, Myron Fleishman, a citizen of the United States, and a resident of 3448 Wilson Avenue, county of Bronx, city and State of New York, have invented a new, original, and ornamental Design for a Toy Whistle or Similar Article, of which the following is a specification, reference being had to the accompanying drawing, forming a part thereof.

Figure 1 is a perspective view of a toy whistle or similar article showing my new design;

Figure 2 is a top plan view thereof;

Figure 3 is a front elevational view thereof;

Figure 4 is a side elevational view thereof; and

Figure 5 is a rear elevational view thereof.

I claim:

The ornamental design for a toy whistle or similar article, as shown.
